CLAIM

The ornamental design for a desk extension socket, as shown and described.

DESCRIPTION

FIG. 1 is a perspective view of a desk extension socket according to the present invention;

FIG. 2 is a first side view of a desk extension socket according to the present invention;

FIG. 3 is a second side view of a desk extension socket according to the present invention;

FIG. 4 is a third side view of a desk extension socket according to the present invention;

FIG. 5 is a fourth side view of a desk extension socket according to the present invention;

FIG. 6 is a top side view of a desk extension socket according to the present invention; and,

FIG. 7 is a bottom side view of a desk extension socket according to the present invention.

The broken lines shown in the drawings are for the purpose of illustrating portions of the desk extension socket and form no part of the claimed design.

1 Claim, 6 Drawing Sheets
